ALBERT M. PIGEON, OF PHILADELPHIA, PENNSYLVANIA.

STOP MECHANISM FOR KNITTING-MACHINES.

1,113,246.

Specification of Letters Patent. Patented Oct. 13, 1914.

Application filed October 25, 1912. Serial No. 797,701.

To all whom it may concern:

Be it known that I, ALBERT M. PIGEON, of Philadelphia, in the county of Philadelphia and State of Pennsylvania, have invented certain new and useful Improvements in Stop Mechanism for Knitting-Machines, whereof the following is a specification, reference being had to the accompanying drawings.

10 The invention relates more particularly to a stop mechanism which may be manually controlled, so as to stop the knitting machine under certain predetermined conditions.

15 The invention is applied to a knitting machine having a needle cylinder which rotates and which is oscillated at times, which knitting machine is provided with a fabric receiving cage, or basket, which rotates with the cylinder and which remains idle during the oscillations of the cylinder.

20 An object of the invention is to provide manually controlled means for stopping the knitting machine before the pattern mechanism throws the parts, so as to begin the rotary motion of the cylinder and fabric receiving basket, whereby the operator may, with safety, reach into the basket to remove the knitted fabric or web without any danger of said cage being rotated while the web 25 is being removed.

25 In the drawings, which show by way of illustration one embodiment of the invention, Figure I, is a side view of a portion of a knitting machine, having my improvements applied thereto. Fig. II, is a front view of the same, the fabric cage being removed. Fig. III, is a detail in section through the frame showing a portion of the 30 pattern mechanism in side elevation, and the controlling arm for stopping the machine. Fig. IV, is a plan view showing the fabric cage and the means for operating the same, and parts of the operating mechanism 35 for the knitting machine. Fig. V, is a sectional view of the lower end of the needle cylinder, the means for supporting the same and the fabric supporting cage or receiver. Fig. VI, is a detail perspective view of certain elements comprised in the stopping mechanism.

40 The invention is embodied in a knitting machine having a needle cylinder which may be rotated for circular knitting, and which may be oscillated for knitting the

45 heel and toe pocket of a stocking. A fabric supporting cage is provided, which receives the web or fabric as it leaves the needle cylinder. This cage is so constructed and operated that it rotates with the cylinder 60 during the circular knitting, but its movement is suspended so that the cage is idle during the oscillating of the needle cylinder. The cage is also provided with an opening in its side through which the operator may withdraw the completed fabric or web. The rotations of the needle cylinder are automatically commenced by the pattern controlling mechanism, and the fabric receiving cage is, at the same time automatically rotated by the needle cylinder. 65

70 In order to prevent the cage being rotated when the operator's hand is inserted in the opening in the cage to withdraw the completed fabric or web, the machine is 75 equipped with a manually controlled stop mechanism which consists of a treadle, adapted to be depressed, which throws a member into the path of movement of a part actuated by the pattern mechanism, so that 80 when the pattern mechanism shifts to bring about the rotation of the fabric cage, said member will be caught and moved so as to shift the driving belt on to the idle pulley, and thus stop the machine. 85

85 The belt and clutch shifting mechanism and the pattern mechanism controlling the same are shown described and claimed in my co-pending application, Serial No. 633,938, filed June 19, 1911. 90

90 Referring more in detail to the drawings, the invention is applied to a knitting machine consisting of a main frame 1, mounted upon suitable legs or standards 2. Mounted in the frame is a driving shaft 3, on which is 95 freely mounted an idle pulley 4, a slow speed pulley 5, adapted to oscillate the needle cylinder, and a high speed pulley 6, adapted to rotate the needle cylinder. The needle cylinder is both rotated and oscillated 100 through a bevel gear 7, which meshes with the bevel gear 8, supported by the shaft 3. This bevel gear 8, may be directly connected to a sleeve attached to the high speed driving pulley 6, and said bevel gear may also 105 be connected through an oscillating segment 9, and reducing gears 60, and 61, to the slow speed driving pulley 5. The clutch for connecting the sleeve carrying the bevel gear 8, to the high or low pulleys is controlled 110

by a lever 10, which is pivoted at 11, to the main frame and carries a stud 12, at its lower end adapted to coöperate with a pattern drum 13. This drum 13, is moved step by step through a pawl and ratchet mechanism indicated at 14, in the drawing. This pawl and ratchet mechanism is thrown into action by a pattern chain 15, carrying pattern lugs or high links 16. The pattern chain is driven through a suitable pawl and ratchet mechanism 17.

The belt is shifted from one driving pulley to another and to the idle pulley by a belt shifting lever 18, which is freely pivoted on a suitable shaft 19, mounted in bearings in the main frame 1. This lever carries spaced pins 20, and 21, between which the belt passes and by the shifting of the lever the belt is carried from one pulley to the other. The belt shifting lever 18, is normally thrown by a spring 22, so as to hold the belt on the idle pulley 4. An arm 23, is rigidly secured to the supporting shaft 19, and said arm carries a latch 24, having a slot 25, therein, and an off-set notch 26. The belt shifting lever 18, is provided with a pin 27, which is adapted to engage the notch 26. The arm 23, is provided with a rearward extension 28, see Fig. I, which carries a member adapted to coöperate with a face cam 29, which is driven by the pattern mechanism which controls the drum, 13. This arm 23, is moved by a spring 30, so that the member carried by the extension is held in contact with said face cam. The parts are so timed and proportioned that when the clutch is shifted to cause the cylinder to rotate, the face cam 29, will shift the arm 23, and through the latch connection 24, move the belt shifting lever 18, so as to bring the belt on to the high speed driving pulley. The pattern mechanism may also shift the lever 18, so as to stop the machine, or so as to cause the needle cylinder to be rotated by the high speed driving pulley 6.

The main frame is provided with a supporting bed 31, in which is mounted a gear 32, attached to the needle cylinder, and this gear 32, meshes with a gear 33, which is fixedly attached to the gear 7, above referred to. It is through these gears that the needle cylinder is either rotated or oscillated. Mounted on the supporting bed is a fabric supporting cage or receiver 34. This fabric receiver is cylindrical in shape and is mounted on a suitable support 35, at its lower end, which permits the fabric receiver to rotate or to remain idle. Said fabric receiver adjacent its upper end is formed with an opening 36, through which the knitted web may be withdrawn by the operator when desired. This fabric supporting cage is rotated with the cylinder by a pin 37, which is carried by the needle cylinder. Mounted on the fabric supporting cage is a lug 38, which lies in

the path of said pin 37. As the cylinder rotates the pin will engage the lug and cause the fabric cage to rotate therewith. A second lug 39, is carried by a yielding member and is adapted to spring behind the pin 37, so that said pin 37, is held between the lugs 38, and 39. The clutch shifting lever 10, shifts a rod 40, which is connected to the sleeve for controlling the clutch which locks the gear 8, to the slow speed or high speed driving pulley. This clutch shifting lever 10, is provided with a bracket 41, which is adapted to engage a pin 42, when said lever 10, is shifted so as to bring about the oscillation of the needle cylinder. The pin 42, is connected to the lug 39, and the movement of the pin 42, throws the lug 39, out of the path of travel of the operating pin 37, so that when the needle cylinder is oscillated, the movement of the fabric receiving cage 85 is suspended. On shifting the clutch lever 10, in the opposite direction, to cause the cylinder to rotate, the lugs 39, will be released and moved back into position behind the pin 37.

From the above, it will be apparent that I have provided a fabric receiving cage which is rotated with the needle cylinder and which remains idle during the oscillations of the needle cylinder. This mechanism for rotating the fabric supporting cage or suspending its movement, *per se*, forms no part of the present invention, but is shown, described and claimed in my co-pending application Serial Number 705,397, filed June 24th, 1912.

In order to stop the knitting machine automatically, upon the starting up of the rotation of the fabric supporting cage, which stop mechanism may be controlled by the operator, I have provided the latch 24, with an arm 43, which extends to the opposite side of the pivot which attaches the latch 24, to the arm 23. A rod 44, is pivoted at its upper end to the arm 43, and said rod is bent at its lower end to form a hook 45. Mounted on a cross shaft 46, supported by suitable bearings in the main frame is an arm 47. Said cross shaft 46, is also provided with a second arm 48. The arm 48, as shown in Fig. II, is located directly in front of the pattern chain 15, and is adapted to be engaged by the pattern lugs 16. When the lugs move into engagement with the arm 48, the arm 47, will be rocked. The rod 44, is normally held out of the path of movement of the arm 47, by a finger 49, carried by a rock lever 50, pivotally supported on the shaft 19. This rock lever 50, has an arm, which is connected to a rod 51, and the rod 51, at its lower end extends through a bracket 52, and is pivotally attached to a foot treadle 53. A spring 54, surrounds the rod 51, and bears at its lower end on the bracket, while the upper end of the spring bears against a collar 55, attached to the rod. 130

This spring normally holds the rod raised and the finger 49, thrown to the right, as viewed in Fig. II. This finger thus positioned holds the rod 44, out of the path of movement of the arm 47, on the cross shaft 43. The rod 44, is moved into the path of the arm 47, when released by a spring 58.

The operation of my device is as follows: When the fabric receiving cage is idle and the operator desires to remove the knitted web, the foot is placed on the treadle 53, and said treadle depressed. This moves the finger 49, to the left, as viewed in Fig. II, and permits the rod 44, to swing into the path of movement of the arm 47. The pattern chain is being moved by its pawling mechanism, and if the pattern lug is brought into action, so as to start into motion the pawling mechanism, which controls the drum 13, so as to shift the clutch lever 10, said lug will first strike the arm 48, and move the arm 47, so as to cause the same to engage the bent end 45, of the rod 44, and pull down on the same. This downward movement of the rod 44, shifts the latch 24, so as to bring the pin 26, into register with the slot 25, and the spring 22, at once shifts the belt shifting lever 18, so as to throw the belt onto the idle pulley, and thus stop the machine. The machine may also be stopped readily by the hand lever 56, which is attached to, and is capable of swinging the latch 24, so as to allow the belt shifting lever 18, to be swung by the spring 22.

It is obvious that minor changes in the details of construction and the arrangement of parts may be made without departing from the spirit of the invention, as set forth in the appended claims.

Having thus described my invention, I claim:

1. In a knitting machine, the combination of a fabric receiver, adapted to rotate with the needle cylinder, and adapted to remain idle during the oscillations of the needle cylinder, and manually controlled means for causing the machine to automatically stop prior to the commencement of the rotation of said fabric receiver.

2. In a knitting machine, the combination of a fabric receiver, adapted to rotate with the needle cylinder and to remain idle during the oscillations of the needle cylinder, a manually shiftable member and means controlled thereby, whereby the pattern mechanism will cause the machine to automatically stop before the clutch shifting lever is moved to cause the fabric receiving cage to rotate.

3. In a knitting machine, the combination of a fabric receiver adapted to rotate with the needle cylinder, and to remain idle during the oscillations of the needle cylinder, a belt shifting lever, a spring for normally throwing the belt shifting lever to stop the

machine, a latch for holding the belt shifting lever with the belt on the driving pulley, and manually controlled means for automatically releasing said latch to stop the machine before the parts of the machine are shifted to start the rotation of the fabric receiving cage.

4. In a knitting machine, the combination of a fabric receiver, adapted to rotate with the needle cylinder, and adapted to remain idle during the oscillations of the needle cylinder, a belt shifting lever, means for yieldingly holding said belt shifting lever with a belt on the idle pulley, a latch for holding said belt shifting lever with the belt on the driving pulley, a rod attached to said latch for shifting the same to release the belt shifting lever, an arm oscillated by the pattern mechanism, manually controlled means for permitting said rod to be engaged by said arm for automatically releasing the latch, through the shifting of the pattern mechanism.

5. In a knitting machine, the combination of a fabric receiver, adapted to rotate with the needle cylinder, and adapted to remain idle during the oscillations of the needle cylinder, a belt shifting lever, means for yieldingly holding said belt shifting lever with a belt on the idle pulley, a latch for holding said belt shifting lever with the belt on the driving pulley, a rod attached to said latch for shifting the same to release the belt shifting lever, an arm oscillated by the pattern mechanism, a rock shaft, means carried by the rock shaft for holding said rod out of the path of movement of said oscillating arm, and a treadle for shifting the rock shaft to permit said rod to be engaged by said arm.

6. In a knitting machine, the combination of a fabric receiver, adapted to rotate with the needle cylinder, and adapted to remain idle during the oscillations of the needle cylinder, a belt shifting lever, means for yieldingly holding said belt shifting lever with a belt on the idle pulley, a latch for holding said belt shifting lever with the belt on the driving pulley, a rod attached to said latch for shifting the same to release the belt shifting lever, an arm oscillated by the pattern mechanism, a rock shaft, means carried by the rock shaft for holding said rod out of the path of movement of said oscillating arm, a treadle for shifting the rock shaft to permit said rod to be engaged by said arm, and a spring for normally holding said treadle raised and said rod out of the path of movement of said arm.

7. In combination in a knitting machine having a rotary and oscillating needle cylinder, a let-off mechanism, a fabric cage with means for rotating it when the needle cylinder is rotated and for allowing it to remain at rest when the cylinder is oscillated,

a pattern mechanism controlling and timing the rotary and oscillatory movements of the cylinder and a connection to be set manually to cause said pattern mechanism to operate the let-off mechanism instead of the cylinder and cage rotating mechanism, substantially as described.

In testimony whereof, I have hereunto signed my name at Philadelphia, Pennsylvania, this twenty-first day of October, 1912. 10

ALBERT M. PIGEON.
